UNITED STATES PATENT OFFICE.

CHARLES B. EMMERICH AND CHARLES C. HEIDLAND, OF ST. LOUIS,
MISSOURI.

COLD-STORAGE BOX.

No. 852,225.

Specification of Letters Patent.

Patented April 30, 1907.

Application filed January 3, 1907. Serial No. 350,639.

To all whom it may concern:

Be it known that we, CHARLES B. EMMERICH and CHARLES C. HEIDLAND, citizens of the United States, and residents of St. Louis, Missouri, have invented certain new and useful Improvements in Cold-Storage Boxes, of which the following is a specification containing a full, clear, and exact description, reference being had to the accompanying drawings, forming a part hereof.

Our invention relates to a cold storage box, and is intended to be detachably positioned on a window sill so as to form a convenient receptacle for food, or commodities which are to be kept cool.

Our invention consists of a box, preferably constructed of sheet metal, which rests on the window sill between the lower ends of the side rails of the window frame, and which box is provided in its side with a door, and also with fastening devices, by means of which the box may be rigidly fixed to the window frame.

In the drawings:—Figure 1 is a horizontal section taken through the lower portion of a window frame, and showing our improved box in plan view on the window sill; Fig. 2 is a perspective view of one end of the box, and showing the fasteners in position before being engaged on the window frame; Fig. 3 is a vertical section taken through the center of the box; Fig. 4 is an enlarged horizontal section taken through a portion of the window frame, showing one corner of the box and one of the fastening devices engaged on the window frame.

Referring by numerals to the accompanying drawings:—1 designates the window sill, 2 the side rails of the window frame, 3 the outer stop, 4 the parting strip, and 5 the lower sash.

6 designates the body of my improved cold storage box, which is preferably rectangular in form, constructed of sheet metal, and open in front.

Extending across the front of the top and bottom edges of the box are the beads 7 and 8, and arranged to close the front of the box is a gravity door 9, the ends of which are provided with wings 10, connected to the end walls of the box 6 by means of pins or bolts 11. When this door is closed, its lower edge rests upon the bead 8, and its upper edge bears against the inside of the bead 7; and

when said door is swung open, it occupies a position adjacent the top of the box, thus in no way interfering with the dishes or food placed in the box.

Formed in the end walls of the box 6 are apertures 12, which are covered by sections 12^a of reticulated material 12^a, thus providing means for ventilating the box.

Formed integral with the front side of the box, at the ends thereof, are the outwardly projecting flanges 13, which are intended to engage against the inner faces of the outer stops 3, when the box is positioned for use; and fixed on the front faces of the beads 7 and 8, adjacent the ends, are keepers 14, in the form of short horizontally arranged tubes, in which are positioned rods 15, the same being loosely mounted so as to be rotated and moved longitudinally. The inner ends of these rods 15 are formed into handles 16, and the outer ends thereof are laterally bent to form fingers 17, the outer ends of which are pointed.

When a box of my improved construction is to be positioned for use, the lower sash of the window is raised, and the box is positioned on the outer portion of the window sill, with the flanges 13 engaging against the inner faces of the outer stops 3, the rods 15 having been previously pulled inwardly so that the fingers 17 occupy positions on the front sides of the flanges 13.

After the box has been thus positioned, the rods 15 are moved outwardly until the fingers 17 bear against the inner faces of the side rails of the window frame, and said rods are now rotated by means of the handles 16 so as to bring the pointed ends of the fingers 17 against the outer faces of the parting strips 4, and said pointed ends engaging in the parting strip very rigidly lock the ends of the box to the window frame.

A box of our improved construction forms a very convenient compartment in which to place food which is to be kept cool, and said box is readily accessible by merely elevating the lower sash for a short distance.

We claim:—

1. A device of the class described, comprising a box, a door normally closing the front thereof, flanges integral with the ends of the box for engaging against the outer stops of a window frame, and means arranged on the ends of the box for engaging the part-

ing strips of the window frame to rigidly hold said box in position in the frame.

2. The combination with a window frame, of a cold storage box positioned on the window sill, flanges integral with the ends of the box for engaging portions of the window frame, and rotating members arranged to slide on the ends of the box for rigidly positioning the box in the window frame.

In testimony whereof, we have signed our names to this specification, in presence of two subscribing witnesses.

CHARLES B. EMMERICH.
CHARLES C. HEIDLAND.
